CLOCK

Ardé Bulova, New York, N. Y., assignor to Bulova Watch Company, Inc., New York, N. Y., a corporation of New York

Application May 3, 1934, Serial No. 723,683

2 Claims. (Cl. 58—46)

My invention relates to spring-driven, hand-and-dial clocks, and is applicable particularly to clocks suitable for mounting in automobiles. An object of the invention is to facilitate the winding, heretofore effected by intermittent or oscillatory rotary movement. So-called rim-wind clocks, useful in vehicle equipment, are wound by spanning the rim with the hand and twisting repeatedly, with or without releasing grasp on the 10 rim, an operation which is neither quick nor especially convenient. A particular advantage of this invention is that it enables the clock to be wound by continuous rotary motion. A further object is to provide a device by which the clock 15 can be thus wound, and which can also be moved for setting of the hands, still another movement of the device releasing a lock.

In the accompanying drawing, forming part hereof:

20 Fig. 1 is a face view of a clock embodying the invention;

Fig. 2 is a side elevation thereof; and

Fig. 3 is a diametrical section on a larger scale with portions in elevation.

25 In the clock shown in Figs. 1-3 there is a supporting part consisting of a cup 2 having a forward flange 3. This part may be secured in place by threaded studs 4, or otherwise. In this embodiment, the clock movement 5, a movement 30 case 6, the dial plate 7, the dial 8 and the bezel 9 are assembled or united to form one rotary unit, turning in the supporting cup 2. An arbor 10 is held rotatably in the center of the back of the supporting cup, and on this arbor a ratchet 11 is 35 fixed. A pawl 12 on the inside of the back of the supporting cup keeps this ratchet and arbor from turning when the clock is wound by turning the rotary unit in one direction, but permits the ratchet, arbor and unit to be turned in the 40 reverse direction in order to re-position the dial for reading, after the clock-spring has been wound. On the forward end of the arbor 10 a wheel 13 meshes a winding wheel 14 which is 45 connected with the main spring or springs inside the movement. A ratchet 15 secured with the wheel 14 or on its shaft coacts with a pawl 16 on the back of the clock movement to hold the clock-spring in wound condition. In the winding 50 operation, the wheel 14 travels, turning on its axis, around the wheel 13, and thus winds the spring. When the rotary unit is turned in the other direction to re-position the dial, the wheels 13 and 14, the arbor 10 and the ratchets 11 and

15 turn as a fixed system, the ratchet 11 turning idly under the pawl 12.

On the dial plate 7 there is a hand-setting train 18. The arrangement of clock wheels being a routine matter, given the purpose, it is unnecessary to illustrate these parts in detail.

At one point on the face of the bezel there is a hollow, projecting boss 19. In this boss and in a hole in the dial plate, a pin 20 is slidable and rotatable, being pressed rearward by a spring 21 10 and yieldingly restrained against full backward movement by a spring 22. A knob 23 on the outer end of the pin is taken between the fingers in order to twirl the bezel 9 and parts turning therewith, until the clock-spring is wound. First, 15 however, the knob 23 and pin 20 are pulled out to release a lock between the rotary part and the supporting part, the simplest form of such lock being provided by the rear end 24 of the pin and a hole 25 in the flange 3. To relieve the 20 arbor 10, which connects the rotary part to the stationary part, of strain when the pin 20 is pulled out, angled lugs 28 may be provided, such lugs being secured to the periphery of the bezel and engaging freely under the stationary flange 3. 25

In order to set the clock hands 26, the knob and pin are pushed in against the action of the spring 22, thus causing a pinion 27 on the pin to mesh the first wheel of the hand-setting train 18, after which turning of the knob and pin about 30 their own axis, without turning the bezel or encircling part, sets the hands.

I claim:

1. A clock having an encircling part rotatable for winding the clock-spring, hand-setting mechanism, and a device on said part by which the part can be turned in continuous rotary motion for winding the spring, said device comprising means slidable and rotatable in said part to engage and actuate the hand-setting mechanism. 35

2. A clock having a supporting part, a rotatable part carrying the clock-movement and the dial, hand-setting mechanism likewise carried by said part, means whereby the clock-spring is wound by turning said part in one direction, means for 45 normally locking said rotary part to said supporting part, and a device on said rotary part providing a knob for turning the part to wind the clock-spring by continuous rotary motion, said device being movable in said rotary part to release said locking means and also being movable to engage and actuate said hand-setting mechanism. 50

ARDÉ BULOVA.
